UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-SEPARATING MEANS.

Application filed October 31, 1921. Serial No. 511,806.

To all whom it may concern:

Be it known that I, RICHARD LESTER Wilcox, a citizen of the United States, residing at Waterbury, in the county of New Haven 5 and State of Connecticut, have invented certain new and useful Improvements in Die-Separating Means, of which the following is a specification, reference being had therein to the accompanying drawings.

10 My invention relates to die separating means, its principal object being to provide simple mechanism for separating the dies of an open die header or upsetting machine.

15 Among other aims and objects of my invention may be recited the provision of a device of the character mentioned with a view to compactness and in which the number of parts are few, the construction simple, the cost of production small, and efficiency of 20 operation high.

The improvements in the details and arrangement of parts will be apparent from an inspection of the accompanying drawings, in connection with the description hereinafter 25 contained, and wherein an embodiment of the invention is disclosed for the purpose of imparting a full understanding of the same.

Having more particular reference to the drawings and in connection with which like 30 reference characters refer to corresponding parts in the several figures;

Figure 1 is a front elevation of a pair of dies for a heading machine or the like and the adjacent supporting mechanism therefor with my improved separating means connected therewith;

Figure 2 is a side elevation thereof partly in section;

Fig. 3 is a fragmentary front elevation of 40 the lower portion of a pair of dies and adjacent parts, as shown in Figure 1, with the separating means applied to the underside thereof, the parts in section being taken generally upon line 3-3 of Figure 4; and 45 Figure 4 is a sectional view of the parts shown in Figure 3, taken generally upon line 4-4 of Figure 3.

It has heretofore been the practice to 50 separate the dies of an open die header or upsetting machine at the wire feed line by parting pins, separating pins or the like, an illustration of such means being shown in Letters Patent No. 1,104,090, dated July 21, 1914; particularly in Figure 4 thereof, and

also in Letters Patent No. 1,108,958, dated 55 September 1, 1914, a heavy flat spring, not shown in either of the above patents, bearing upon the upper end of each of the parting pins or separating pins, which move in a path at substantially a right angle to the 60 movement of the dies. With such mechanism the die cap or other part or parts that support the pins must be machined with great care and exactness and each must be in correct alignment with each other and 65 the groove formed by the angular corner faces of the dies, when the dies are in proximity to the wire feed line. If the pins are not so arranged, the lower pointed end thereof will not register with said groove, thus 70 having a tendency to cramp the dies and apply an unequal pressure thereto at different points throughout their length. If this occurs, the dies may be separated more at one 75 end than at the other, and if perchance the minimum separation is at the inner end of the dies a defective feed of the wire results and the end of the wire may abut against the dies and stop the feed.

As the pins are of substantial length the 80 element in which they are mounted must of necessity be of substantial height to provide proper support therefor and this height, as well as the pin operating springs, requires 85 space that can otherwise be advantageously utilized.

All of the above and other objections of the heretofore conventional method for separating the dies are obviated in my improved 90 device, which occupies the minimum amount of not otherwise required space, the necessity of fine machining of the parts is entirely eliminated, and in these, and many other ways, produces results that are advantageous and insure certainty and efficiency in operation, and with mechanism 95 that is of comparatively simple design.

Having more particular reference to the 100 drawings, numerals 10 and 11 represent the dies, which are of the usual form with corner angular faces 12 which unite to form a V shaped groove substantially as shown in Figures 1 and 3, wherein the dies are near the wire feed line, this being perpendicular to the line 2-2 of Figure 1. A 105 piece of wire designated 13 is shown in section at this feed line.

The bed plate upon which the dies are sup-

ported is designated 14, and the cap or cover over the top thereof 15.

All of the mechanism above described is of a well known form and operates in an 5 equally well known manner and therefore needs no further description herein.

The means for actuating the dies is not shown herein for the above reason, but the same travel between the wire feed line and 10 the upsetting line, which latter line is designated α — α in Figure 1. From the wire feed line to the upsetting line the dies are positively actuated by relatively powerful mechanism to cut off a piece of the wire rod but 15 are usually returned from the upsetting line by spring mechanism.

As shown the dies are held against end-wise movement in the supporting means by the plates 16 and 17, this being only one of 20 the many ways by which the same result may be accomplished.

Pivotaly mounted within the cover 15 upon the stud 18 are one or more levers 19 upon each of which is a lug 20 which rests 25 within the V groove of the dies when the same are near or at the wire feed line.

The necessary grooves 25 are formed in the underside of the cover 15 to permit free movement of the levers 19.

30 Movable within the cover 15 are plungers 21, corresponding in number with the levers 19, and each of which is surrounded by a coil spring 22 within the bore 23. These plungers are limited in their downward movement by the nuts 24 threaded in the shank thereof, thus providing means to vary the relative position of the plungers and the tension of the springs 22.

When the dies are at or near the wire feed 40 line, the lug 20 on the lever 19 is in the V groove formed by two of the faces of the dies and held therein by the spring plunger 21. As the dies travel from the wire feed line to the upsetting line, the lever 19 is moved upon its pivot mounting against the tension of the springs 22 by the die 11, thus permitting the latter to pass thereunder. During the return movement, as the dies approach the wire feed line, the lug 20 is moved 45 downwardly into the V groove formed between the dies by the spring plunger 22, which action separates the dies, sufficiently to permit the wire to pass therebetween.

50 Thus my improved die separating mechanism requires only a minimum amount of space, is composed of few parts, and in these and other ways objections to the mechanism heretofore commonly utilized for this purpose are eliminated and many obvious advantages secured.

I have shown in Figures 1 and 2 my improved mechanism as applied to the top side of the die, but obviously it will operate 55 equally as well if applied to the underside thereof, as shown in Figures 3 and 4, the nu-

merical designations 19^a, 20^a, 21^a, 23^a and 25^a therein corresponding with the above mentioned parts and structures designated 19, 20, 21, 23 and 25, or if desired, it may be used upon both top and bottom.

70 There are minor changes and alterations that can be made within my invention, aside from those herein suggested, and I would therefore have it understood that I do not limit myself to the exact construction herein shown and described, but claim all that falls fairly within the spirit and scope of the appended claims.

Having described my invention, what I claim as new and desire to secure by Letters 80 Patent is:

1. In combination with dies of a heading machine or the like; of means for opening the dies wherein each of the dies has a face thereon that co-operates with a similar face upon another die to form a groove when the dies are in operative relation to each other, comprising in part a lever, and means for applying pressure to said dies through said lever to separate the dies when substantially in register with the wire feed line.

90 2. In combination with the dies of a heading machine or the like; of means for opening the dies wherein each of the dies has a face thereon that co-operates with a similar 95 face upon another die to form a groove and comprising in part a yieldingly actuated lever and means for applying pressure to the dies through the lever to separate the dies when substantially in register with the 100 wire feed line.

105 3. In combination with the dies of a heading machine or the like; of means for opening the dies wherein each of the dies has a face thereon that co-operates with a similar 110 face upon another die to form a groove when the dies are in operative relation to each other, comprising a lever having a part thereon that projects into said groove when the dies are approximately at the wire feed line; and yielding means engaging said lever.

115 4. In combination with the dies of a heading machine or the like; of means for opening the dies wherein each of the dies has a face thereon that co-operates with a similar face upon another die to form a groove when the dies are in operative relation to each other, comprising a lever having a part thereon that projects into said groove when the dies are approximately at the wire feed line; and yielding means engaging said lever, the mounting of said lever being upon one side of the wire feed line.

120 5. In combination with the dies of a heading machine or the like; of means for opening the dies wherein each of the dies has a face thereon that co-operates with a similar face upon another die to form a groove when the dies are in operative relation to 125

130

each other, comprising a lever having a part thereon that projects into said groove when the dies are approximately at the wire feed line; and yielding means engaging said lever, 5 the yielding means being upon one side of the wire feed line.

6. In combination with the dies of a heading machine or the like; of means for opening the dies wherein each of the dies has a 10 face thereon that co-operates with a similar face upon another die to form a groove when the dies are in operative relation to each other, comprising a lever having a part thereon that projects into said groove when the dies are approximately at the wire feed line; and yielding means engaging said 15 lever, the mounting of said lever being upon one side of the wire feed line and the yielding means upon the other side thereof.

20 7. In combination with the dies of a heading machine or the like, wherein each die has a face thereon that co-operates with a similar face upon another die to form a groove when the dies are in operative relation to each other; of means for supporting the dies; a recessed cap or cover therefor; means for separating the dies, comprising a lever mounted in a recess in the cap or cover and having a part thereon that projects into said groove when the dies are at the wire feed line.

25 8. In combination with the dies of a heading machine or the like, wherein each die has a face thereon that co-operates with a similar face upon another die to form a groove when the dies are in operative relation to each other; of means for supporting the dies; a recessed cap or cover therefor; means for separating the dies, comprising a lever mounted in a recess in the cap or cover and having a part thereon that projects into said groove when the dies are at the wire feed line.

30 9. In combination with the dies of a heading machine or the like, comprising a lever mounted in a recess in the cap or cover and having a part thereon that projects into said groove when the dies are at the wire feed line; and yielding means connected with the cap or cover having contact with the lever. 40

35 9. In combination with the dies of a heading machine or the like, wherein each die has a face thereon that co-operates with a similar face upon another die to form a groove when the dies are in operative relation to each other; of means for supporting the same; a recessed cap or cover therefor; means for separating the dies, comprising a lever mounted in a recess in the cap or cover and having a part thereon that projects 45 into said groove when the dies are at the wire feed line; yielding means connected with the cap or cover having contact with the lever. 50

40 10. In combination with the dies of a heading machine or the like, having corners which co-operate to form a groove when in operative relation to each other; of means for supporting the same; a recessed cap or cover therefor; means for separating said dies, comprising a lever mounted in a recess in the cap or cover applying pressure to a part within said groove. 55

45 In testimony whereof, I have hereunto 60 affixed my signature.

RICHARD LESTER WILCOX.
